GRANDON E. ECKERT, OF EAST LIVERPOOL, OHIO, ASSIGNOR TO THE E. THOMAS & SONS COMPANY, OF EAST LIVERPOOL, OHIO, A CORPORATION OF OHIO.

INSULATOR.

Application filed June 21, 1923. Serial No. 646,844.

My invention relates to insulators, and particularly to suspension insulators of the link type. The object of my invention is to improve the construction of the link, not only to facilitate its assembly with the insulator, but also to effect a more uniform distribution of the stresses imposed upon the insulator under load.

In the accompanying drawings—

10 Fig. 1 is a broken side elevation of a suspension insulator with which is associated a link in which my invention is embodied in one form;

15 Fig. 2 is a side elevation of the link alone, drawn to a larger scale;

Fig. 3 is a section on the line 3—3, Fig. 2;

15 Fig. 4 is an enlarged cross section through the bearing area of the link prior to load strain;

20 Fig. 5 is a similar view showing its deformation under load;

Figs. 6 and 7, Figs. 8 and 9, Figs. 10 and 11, and Figs. 12 and 13 are views corresponding to Figs. 4 and 5, but illustrating 25 various modifications.

The link commonly used with suspension insulator units of the Hewlett type, comprises merely a copper rod of appropriate diameter bent to horse-shoe shape and headed 30 at its opposite ends. For some conditions this construction is satisfactory. When the insulators are called upon to stand heavy strains, however, a link of round cross section is objectionable by reason of its rigidity, and the fact that its contour is such that 35 the stresses imposed on the porcelain are concentrated in a narrow area, with the result that fractures of the porcelain not infrequently occur.

40 Again, it has been customary to form at the ends of the link shanks cylindrical heads of considerable depth for engagement with either connectors between adjacent insulator units, or adapters at the top and bottom of 45 the insulator string. These heads not only considerably increase the necessary diameter of the passageway through the insulator body, but add to the difficulty of threading the link therethrough.

50 The present invention provides a link structure which not only facilitates the threading of the link through the passage in the insulator, but is of such shape in its bearing area that the strains under load 55 are more widely and evenly distributed up-

on the insulator body. For the latter purpose the bearing area of the link is so shaped that it possesses markedly greater pliability and is deformable under load and furthermore, its shape is so predetermined that upon deformation under load its bearing area is so increased that a distribution of load strains over a larger area of the insulator results, and thus prevents the concentration of stresses which has heretofore resulted in injury to the insulator.

In the accompanying drawings, I have illustrated in Fig. 1 a string of Hewlett insulators 15, each having its hub pierced by oppositely faced interlinked passages 16 and 17 to accommodate links which engage connectors 18, or top and bottom terminal fittings such as the adapters 19. The links comprise shanks 20 united by the curved bearing area 21 and terminating in slabbed off heads 22. Instead of the usual cylindrical heads, the shoulders 23 at the outer faces of the shanks are omitted, and the corresponding corner rounded off, as indicated at 24. The arcuate surface 24 thus afforded, facilitates the stringing of the link through the passage 16, since no sharp edge is presented at the outer margin of the head, but the rounded corner slides freely through the passageway 16. The support afforded by 24 the head is not materially lessened since the shoulder which engages the connector or terminal fitting is retained, except for a slight arcuate extent.

The loop 21 of the link constitutes the 90 portion thereof which lies within the passageway 16 and bears against the hub 25 of the insulator, transmitting to the latter the heavy mechanical strains of the line load. In order to distribute these strains as widely 95 as possible, the loop of the link is so pre-shaped that under sufficient load it is deformed and affords a transverse bearing area of much greater extent than has heretofore been usual. This may be accomplished 100 in various ways. In the construction shown in Figs. 1 to 5 the loop of the link is deformed from its normal circular cross section to an approximate arcuate section, the curvature of the bearing face having a 105 greater radius than that of the shank. This face of the link is scored by longitudinally extending lateral recesses 26. An intermediate longitudinally extending recess 27 is also formed in the outer surface of the loop, 110

Inasmuch as the deformation of the loop is effected without reducing the total cross sectional area—that is to say, without reducing the amount of metal in the link, or materially lengthening the latter—the full mechanical strength of the link is maintained, although its cross sectional contour is so altered that the loop is more pliable. This characteristic renders it possible to maintain the normal cross sectional dimensions of the loop well within the diameter of the passage 16, so that the link may be readily threaded therethrough while when the link is placed under load the bearing area is deformed by the strain from its normal contour, indicated in Fig. 4, to its stressed contour, indicated in Fig. 5. In the latter condition a much greater bearing area is afforded. Thus, the longitudinally extending wings 28 are drawn against the wall of the passageway 16, and the channels 26 are practically closed. It will be obvious from Fig. 5 that the stressed area of the hub 25 of the insulator increases from the relatively narrow band indicated at 29, Fig. 4, to the broad band 30 of Fig. 5, through which the heretofore concentrated strains are now disseminated.

This result can be accomplished in many ways. Thus, as shown in Figs. 6 and 7, the initial cross section of the link-loop may be substantially U-shaped, the sides 31 and 32 flattening out under stress as indicated in Fig. 7.

The single central channel 33, shown in Figs. 6 and 7, may be supplemented by lateral channels 34 and 35, as indicated in Figs. 8 and 9.

In Figs. 10 and 11, the channels of Figs. 8 and 9 are supplemented by complementary channels 36 and 37, formed in the bearing face of the link.

In Figs. 12 and 13 the shape of the channels is further modified. Thus, the bearing surface is cut by narrow channels 38, 39 and 40, while the opposite face of the link body is indented by narrow channels 41 and 42, staggered with relation to those on the opposite face of the link, and producing in effect a corrugated web loop.

The increased pliability in the loop area of the link, which is as usual of copper or the like, has the further advantage of causing the loop to hug the bearing surface of the passageway evenly at all points. This is not the case with links of round or other

semi-rigid cross section, unless the longitudinal curvature of the loop corresponds exactly to the longitudinal curvature of the passageway—and this seldom happens. With the old type of link, the lack of exact coincidence at all points between the cooperating surfaces results in localized strains by reason of the unyielding cross sectional contour of the loop. These localized strains—occurring at different points in both the same and in the opposed passageways—have proved one of the great sources of mechanical injury to insulators of this type.

By the present invention, the loop of the link is rendered sufficiently pliable under strain to adapt itself to the curvature of the passageway, and thus, as above stated, hugs it at all points. At the same time, the transverse stress area is markedly increased over the old cylindrical loop. Again, the initial cross sectional contour of the present loop is so restricted that the link may be readily threaded through its passageway 16, while its full transverse bearing area does not become effective until the loop is flattened under strain.

These features are susceptible of embodiment in various other forms of construction, and consequently the details shown are to be regarded as merely illustrative of the broader thoughts which I claim as my invention.

I claim—

1. A link for insulators, comprising a bearing loop area longitudinally channelled to facilitate its transverse deformation under load.

2. A link for insulators, comprising a bearing loop area longitudinally channelled on both faces to facilitate its transverse deformation under load.

3. For use in a supporting fitting provided with seats, an insulator-engaging link of generally horseshoe shape, comprising a bar of metal having its ends offset toward each other to form shouldered heads adapted to freely engage the seats of said supporting fittings, the outer surfaces of said heads being rounded and slabbed off, said surfaces merging substantially without break with the outside of the link to facilitate the threading of the link through a curved passage formed in the insulator.

In testimony whereof I have signed my name to this specification.

GRANDON E. ECKERT.
